UNITED STATES PATENT OFFICE.

DAVID L. WINTERS, OF ANNAPOLIS, MARYLAND.

CARBURETER CONTROL.

1,286,474.

Specification of Letters Patent.

Patented Dec. 3, 1918.

Application filed December 27, 1916. Serial No. 139,227.

To all whom it may concern:

Be it known that I, DAVID L. WINTERS, a citizen of the United States, residing at Annapolis, in the county of Anne Arundel 5 and State of Maryland, have invented certain new and useful Improvements in Carbureter Controls, of which the following is a specification.

This invention relates to the method and 10 means for controlling the carbureter of an internal combustion engine of a motor car or aeroplane, and the invention has for its primary object the provision of means and apparatus for carbureter control of the 15 character described, whereby the density of the mixture furnished the engine by the carbureter may be economically regulated from the operator's seat to minimize the necessity of throttling the charge, and the 20 loss of power and fuel resulting therefrom.

A further object of this invention is to provide means for controlling a carbureter so operable as to enable the vehicle driver to determine the most efficient mixture for 25 the engine under varying load conditions and varying conditions of temperature, altitude, humidity, and the like. A still further object of this invention is the provision of a carbureter with means operable from the 30 driver's seat, whereby the volume of the charge may be increased or diminished which will by means of an auxiliary air inlet co-operating with the carbureter control.

With the foregoing and other objects in 35 view, as will from time to time hereinafter appear, this invention consists in the peculiar construction and combination of the various co-operating elements of a carbureter control as set forth in the following specification and more particularly pointed out in 40 the appended claims.

In the operation of an internal combustion engine it is necessary that the most efficient mixture of fuel be immediately available at certain times, due to changes in load 45 or atmospheric conditions. In the effort to overcome these variances of operation it is common practice to adjust the carbureter by hand while the vehicle is standing still 50 in order to produce what is believed to be the most efficient mixture for the engine. Under these conditions however the most efficient adjustment cannot be obtained, as such adjustment to be as near perfect as possible must be made while the vehicle is in

motion and the engine is operating under normal or abnormal load conditions. With the view to remedying this defect I have invented the mechanism hereinafter described.

Referring to the accompanying drawings 60 forming a portion of this specification and illustrating the preferred embodiment of the invention, as well as a modification thereof, and wherein the same reference characters indicate the same parts wherever used, 65

Figure 1 is a side elevation of a portion of an automobile, partly cut away, to show the device as applied to a carbureter;

Fig. 2 is a detail side elevation partly in section and partly broken away, showing a 70 modification of my invention, and

Fig. 3 is a detail perspective of the operating levers.

4 designates a carbureter of any suitable type provided with the usual air inlet 75 and the usual gasoline supply needle valve 5, controlled by a stem 6 having a knurled cap 7 at the upper end thereof to ordinarily permit of manual adjustment, the fuel supply to the engine being controlled 80 by a throttle valve 8 carried by a shaft 9 to which is attached a lever 10 provided with a ball joint 11 adapted to receive a rod 12 which in turn is provided with a second ball joint 13 adapted to engage the 85 socket upon a curved extension 14, of a rod 15 extending upwardly along the steering column 16 to a point below the steering wheel, where the rod 15 is provided with a collar 17 and an operating handle 18, the 90 lower portion of the rod 15 having a collar 19 thereon adjacent the extension 14.

In the construction shown in Fig. 1, the stem 6, of the needle valve 7 is encircled by means of a collar 20 held in place 95 thereon by a lock nut 21 and carrying an arm 22 which is connected to a rod 23 carrying a joint 24 adapted to engage an arm 25 secured to a cylindrical shaft 26 which encloses the member 15 and extends upwardly 100 along the steering column 16 to a position below the steering wheel, where said member 26 is provided with a handle 27 and a slot 28 flanked by up-standing ears 29, 30 through which is passed a bolt 31 provided 105 with a wing nut 31' the purpose of which will hereinafter be explained. The upper portion of the member 26 bears against the collar 17 carried by the shaft 15 and the lower portion of the member 26 abuts 110

against the collar 19 adjacent the extension 14 of the member 15.

The collar 17 has depending therefrom a lug 32 bearing against the upper end of the member 28 and the member 28 has a similar upstanding lug 33 bearing against the lower face of the collar 17, the construction being such that a limited rotary movement of each member independently of each other is permitted until the lugs come in contact when the two members will move together as hereinafter explained.

In the modification shown in Fig. 2, which is more particularly adapted for carburetors in which the feed of gasoline from the gasoline supply is normal at all times, the crank extension 25 of the cylindrical member 26 carries, by means of the member 24 a rod 34 carrying a ball 35 adapted to engage the socket 36 of a shaft 37 of an auxiliary air valve 38 placed in the manifold 39 at any suitable point. The construction of the throttle valve and its controlling mechanism in the modification is the same as that described in Fig. 1.

The operation of the device is as follows:

In the construction illustrated in Fig. 1 the operating levers 18 and 27 are normally clamped together by means of the wing nut 31' sufficiently tight to insure joint movement thereof upon the movement of either one of the same, but not however sufficiently tight to prevent the independent movement or shifting of lever 27 to effect a readjustment of the mixture of air and gasoline, during which re-adjustment the lever 18 is preferably held by the thumb, or by the rack on the steering column, as may be found most convenient, this movement being limited by the lugs 32-33 to prevent the operator using too rich or too lean a mixture, as the case may be, for effective combustion.

Under some working conditions, especially those due to change of altitude, temperature, humidity, or the like, it has been found desirable in internal combustion engine operation to permit the inflow of additional air through the inlet manifold. In order to provide for this the construction illustrated in Fig. 2 is placed in the same position on the steering column 16. In this construction the carburetor is provided with means for permitting a continuous flow of gasoline of equal volume at all times, the only adjustment being that of the air from and to the carburetor and the manifold. In this construction the throttle valve 9 is operated as described above and the auxiliary air valve 38 operated by means of the handle 27 through the medium of the members 25, 31 and 37 to secure the proper amount of additional air passing into the manifold 41, when upon proper response from the engine showing that the correct mixture is being obtained and the most efficient mix-

ture used with relation to the speed of the machine, the operating members 26 and 15 remaining clamped together sufficiently tight to permit of simultaneous operation by means of either of the levers 18-27.

As shown in Fig. 2, the auxiliary air valve is preferably capable of a limited movement during which it remains closed, thus said valve may be operated in either its opened or closed position by shifting its operating lever.

It will be seen that by the construction above described independent operation of the air throttle, and fuel control of the carburetor may be effected in the preferred form, and that simultaneous operation of both may be effected when the proper and most economical mixture has been ascertained, and that by the modification shown a proper and independent adjustment of the throttle valve of the carburetor and the auxiliary air valve of the manifold may be made, the operating chambers thereof remaining fastened together by the medium of the mechanism described, whereupon a simultaneous operation of the two valves may be effected in order to continue the supply of the proper charge.

I realize that considerable variation is possible in the details of construction and arrangement of parts without departing from the spirit of my invention, and I therefore do not limit myself to the specific form shown and described. As an instance of this, any well known means may be employed to effect, upon the operation of lever 27, a more extended movement of the fuel valve stem 7.

Having thus described my invention what I claim as new and desire to secure by Letters Patent is:

1. In a device of the character described the combination with a manifold provided with a pair of inlets, of a pair of valves, one for controlling each of said inlets, means for independently operating said valves and means to cause said independent means to operate simultaneously.

2. In a device of the character described the combination with a manifold provided with a pair of inlets, of a pair of valves, one for controlling each of said inlets, means within the reach of the driver for independently operating said valves, and means operable at the will of the driver to cause said controlling means to operate in unison or separately.

3. In a device of the character described the combination with a manifold provided with a pair of inlets, of a pair of valves, one for controlling each of said inlets, independent controlling means including a control lever within reach of the driver, extending from each of said valves, and means adapted to cause a simultaneous operation

of both of said levers and to permit of independent operation of either of said levers.

4. In a device of the character described the combination with a manifold provided 5 with a pair of inlets, of a pair of valves, one for controlling each of said inlets, an arm carried by each of said valves, a link carried by each of said arms, a rod provided with an extension connected to each of said 10 links, a lever on each of said rods, and means adapted to releasably tie both of said rods together at the will of the operator.

5. In a device of the character described the combination with a manifold provided 15 with a pair of inlets, of a pair of valves, one for controlling each of said inlets, an arm carried by each of said valves, a link carried by each of said arms, a rod provided with an extension connected to each of said 20 links, a lever on each of said rods, means adapted to releasably tie both of said rods together at the will of the operator, said means comprising a clamp encircling said rods, and means for causing said clamp to 25 bind said rods to tie them together.

6. In a device of the character described, the combination with a carbureter, of independent means for controlling the fuel supply valve thereof, independent means for operating the throttle valve thereof, and means for causing said independent means to operate simultaneously.

7. In a device of the character described, the combination with a carbureter, of means 35 within reach of the driver adapted to control the fuel supply valve of said carbureter, means within reach of the driver adapted to control the throttle valve thereof, and means operable at the will of the driver to 40 cause said controlling means to operate in unison or separately.

8. In a device of the character described, the combination with a carbureter having a fuel supply valve and a throttle valve, independent 45 controlling means extending from each of said carbureter valves to a point within reach of the driver, said means comprising a throttle control lever, a fuel supply control lever, and means adapted to cause 50 a simultaneous operation of both of said

levers and to permit of independent operation of either of said levers.

9. In a device of the character described, the combination with a carbureter having a fuel inlet valve, an arm carried by said 55 valve, a link carried by said arm, a rod provided with an extension connected to said link, a lever on said rod, a throttle valve for said carbureter, an arm on said valve, a link carried by said arm, and a rod having an 60 extension adapted to engage said link, said rod being adjacent said first mentioned rod, and means adapted to releasably tie both of said rods together at the will of the operator. 65

10. In a device of the character described, the combination with a carbureter having a fuel inlet valve, an arm carried by said 70 valve, a link carried by said arm, a rod provided with an extension connected to said link, a throttle valve for said carbureter, an arm on said valve, a link carried by said arm, and a rod having an extension adapted to engage said link, said rod being adjacent said first mentioned rod, and means adapted to releasably tie both of said rods together 75 at the will of the operator, said means comprising a clamp encircling said rods, and means for causing said clamp to bind said rods to tie them together.

11. In a device of the character described, the combination with a carbureter having a fuel inlet valve, an arm carried by said 80 valve, a link carried by said arm, a rod connected to said link, a throttle valve for said carbureter, an arm on said valve, a link carried by said arm, a rod connected with said link, said rod being adjacent said first mentioned rod, a collar on said first mentioned rod, a lug on said first mentioned rod, a lug on said second mentioned rod adapted to 85 move into contact with the lug on said first mentioned rod, and means for causing both of said rods to operate together.

In testimony whereof I affix my signature in the presence of two witnesses.
